UNITED STATES PATENT OFFICE

EDGAR B. SYMONS, OF HOLLYWOOD, CALIFORNIA, ASSIGNOR TO NORDBERG MANUFACTURING CO., OF MILWAUKEE, WISCONSIN, A CORPORATION OF WISCONSIN

YIELDING RELEASE FOR CRUSHER BOWLS

Application filed August 5, 1931. Serial No. 555,215.

My invention relates to an improvement in crushing machines and has for one object the provision of an improved yielding release for the bowl or concave of a gyratory crusher. 5 Another object is the provision of improved yielding means for normally holding the bowl fixed in predetermined crushing position. Other objects will appear from time to time in the course of the specification and 10 claims.

The invention is more or less diagrammatically indicated in the accompanying drawings, wherein

15 Figure 1 is a vertical section;
Figure 2 is a partial elevation; and
Figure 3 is a detail of a spring abutment segment.

20 Like parts are indicated by like symbols throughout the specification and drawings.

25 Referring to the figures, A generally indicates a fixed main frame for the crusher. Its upper edge is provided with an outwardly projecting flange A¹, the opposite sides of which are bevelled or inclined as at A² A³.

30 B generally indicates a shaft, on the upper end of which is mounted a crushing head or cone B¹ having an outer generally conic surface B². The supporting means for the cone and shaft are omitted from the present drawings, since they do not of themselves form part of the present invention.

35 It will be understood that any suitable means may be employed for supporting and gyrating the shaft and head. B³ indicates a crushing mantle positioned upon the head B¹. It may be held in position as by the sleeve B⁴ and the locking member B⁵. The details of the locking means are omitted, since they do not of themselves form part of the present 40 invention.

45 C generally indicates a bowl supporting ring which is positioned upon the flange A¹. It is provided with a concavity generally indicated as C¹, which receives the flange A¹, and which has inclined surfaces C² C³ opposed to the corresponding surfaces A² A³ of the flange A¹. The member C is provided with an internally screwthreaded portion C⁴.

50 D generally indicates the bowl structure proper, which may include an outer generally

cylindrical portion D¹ screwthreaded to mesh with the screwthreading C⁴, as at D². Any suitable means may be employed for imparting relative rotation to the members C and D, whereby to effect vertical adjustment of the 55 bowl structure D. D³ indicates a generally conic inner wall of the bowl structure, herein shown as overhanging the head B¹. The bowl liner D⁴ may be secured thereto in any suitable manner as by the lugs D⁵ engaged by 60 the hooks or bolts D⁶ with the adjusting shims D⁷ and the lock nuts D⁸.

It will be understood that in the normal use of the device, the bowl liner D⁴ is held 65 normally fixed in the position in which it is shown, while the head, including the mantle B³, is gyrated to effect the crushing action. In order, therefore, to hold the ring C normally locked against the flange A¹ in the position shown in Figure 1 I provide the 70 following means. I may employ a number of bolts E¹⁰ E¹⁴ which pass through apertures E¹ E² in the members A¹ and C respectively. The bolts may be headed or provided with nuts at top and bottom. It will be 75 noted, as in Figure 2, that the bolts E are arranged in two series. E¹⁰ indicate bolts having heads E¹¹ at the lower ends. The bolts E¹⁰ project upwardly through the ring C and through the upper segments E⁶, being 80 provided with upper nuts E¹². Another set of bolts E¹⁴ are headed at the top as at E¹⁵, and project downwardly along the frame A, to support the lower segments E⁸ by means 85 of the nuts E⁴. The upper and lower segments are provided with spring positioning abutments E¹⁶ and it will be noted from Figure 2 that these abutments on the lower segments are aligned with the heads E¹¹ of the bolts E¹⁰, while the abutment E¹⁶ of the 90 upper segments E⁶ are aligned with the bolt heads E¹⁵. The bolts E¹⁰ and E¹⁴ alternate, so that the springs E¹⁷ E¹⁶ of each series are alternately positioned by bolts passing through them and by the spring abutments 95 E¹¹ E¹⁶ and E¹⁵ E¹⁶.

G indicates an upper housing which may be positioned upon the member C within the upper springs E¹⁰. Preferably it extends above the top segments E⁶. The member G, 100

therefore, serves as a guide for the upper segments B⁶ and the springs E¹⁸, preventing any substantial lateral movement thereof. Similarly the main frame A serves as a guide for the lower segments E⁵ and the lower springs E¹⁷.

In the use of the present device, the upper and lower sets of springs are of sufficient strength to hold the ring C, and thus the 10 crushing liner D⁴, normally fixed in crushing position. In case tramp iron or other uncrushable material penetrates the crushing zone, the springs will permit the entire bowl structure, including the ring C, to tilt 15 upwardly to permit the passage of the uncrushable material or to prevent the breakage of the crusher.

It will be realized that whereas I have described and shown a practical and operative 20 device, nevertheless many changes may be made in size, shape, number and disposition of parts without departing from the spirit of my invention. I, therefore, wish my drawings to be taken as in a broad sense illustrative and diagrammatic rather than as limiting me to the precise details of the present showing.

I claim:

1. In a gyratory crusher, a fixed circumferential frame member, a crushing head and means for gyrating it, a bowl surrounding the head, supporting means for the bowl tiltably mounted upon the upper edge of the frame member, and yielding means for holding 30 said supporting means normally fixed in relation to said frame, said means including a set of springs positioned above said supporting means and a set of springs positioned below said supporting means, abutment members confining the upper and lower ends respectively of said sets of springs, and compression members, extending respectively upwardly and downwardly from said bowl supporting means in securing relationship with the upper and lower abutment members 35 respectively.

2. In a gyratory crusher, a fixed circumferential frame member, a crushing head and means for gyrating it, a bowl surrounding 50 the head, supporting means for the bowl tiltably mounted upon the upper edge of the frame member, and yielding means for holding said supporting means normally fixed in relation to said frame, said means including a set of springs positioned above said supporting means and a set of springs positioned below said supporting means, abutment members confining the upper and lower ends respectively of said sets of springs, and compression members, extending respectively upwardly and downwardly from said bowl supporting means in securing relationship with the upper and lower abutment members 55 respectively, said compression members including headed bolts, the heads of said bolts

being adapted to serve as spring positioning abutments.

3. In a gyratory crusher, a fixed circumferential frame member, a crushing head and means for gyrating it, a bowl surrounding the head, supporting means for the bowl tiltably mounted upon the upper edge of the frame member, and yielding means for holding 70 said supporting means normally fixed in relation to said frame, said means including a set of springs positioned above said supporting means and a set of springs positioned below said supporting means, abutment members confining the upper and lower ends respectively of said sets of springs, and compression members, extending respectively 75 upwardly and downwardly from said bowl supporting means in securing relationship with the upper and lower abutment members respectively, the upwardly extending and downwardly extending compression members 80 alternating.

4. In a gyratory crusher, a fixed circumferential frame member, a crushing head and means for gyrating it, a bowl surrounding 90 the head, supporting means for the bowl tiltably mounted upon the upper edge of the frame member, and yielding means for holding said supporting means normally fixed in relation to said frame, said means including 95 a set of springs positioned above said supporting means and a set of springs positioned below said supporting means, abutment members confining the upper and lower ends respectively of said sets of springs, and compression members, extending respectively 100 upwardly and downwardly from said bowl supporting means in securing relationship with the upper and lower abutment members respectively, the upwardly extending and downwardly extending compression members alternating, each such compression member including a headed bolt, said bolt heads being adapted to serve as spring positioning abutments for springs of one set, 105 the bodies of the bolts being adapted to serve as spring aligning means for spring of the other set, the heads of the upwardly extending bolts abutting against the frame member, the heads of the downwardly extending 110 bolts abutting against the bowl.

5. In a gyratory crusher, a normally fixed circumferential frame member, a crushing head within said frame member and means for gyrating it, a bowl, surrounding said head, said bowl being tiltably positioned upon the upper edge of the frame member, the frame member being provided with a flange outwardly extending about its upper edge, the bowl including a portion overlying 120 said flange, and yielding means for holding the bowl normally fixed in relation to the frame, said means including a lower set of springs positioned about the frame member and vertically aligned beneath the flange, 125

- and an upper set of springs vertically aligned with the lower set of springs and positioned above the portion of the bowl which overlies the flange, abutment means for the upper 5 ends of the upper springs and for the lower ends of the lower springs, and compression members therefor, the compression members for the lower set of springs connecting the overlying portion of the bowl 10 with the lower abutment means, the compression members for the upper set of springs connecting the flange of the frame with the upper abutment means.
6. In a gyratory crusher, a normally fixed 15 circumferential frame member, a crushing head within said frame member and means for gyrating it, a bowl surrounding said head, said bowl being tiltably positioned upon the upper edge of the frame member, the frame member being provided with a flange outwardly extending about its upper edge, the bowl including a portion overlying said flange, and yielding means for holding the bowl normally fixed in relation to the frame, 20 said means including a lower set of springs positioned about the frame member and vertically aligned beneath the flange, and an upper set of springs vertically aligned with the lower set of springs and positioned above 25 the portion of the bowl which overlies the flange, abutment means for the upper ends of the upper springs and for the lower ends of the lower springs, and compression members 30 therefor, the compression members for the lower set of springs connecting the overlying portion of the bowl with the lower abutment means, the compression members for the upper set of springs connecting the flange of the frame with the upper abutment means, said 35 compression members being headed, the heads of the compression members for each set of springs being adapted to serve as spring positioning abutments for the adjacent ends of the springs of the opposite set.
7. In a gyratory crusher, a normally fixed 40 circumferential frame member, a crushing head within said frame member and means for gyrating it, a bowl, surrounding said head said bowl being tiltably positioned upon the upper edge of the frame member, the frame member being provided with a flange outwardly extending about its upper edge, the bowl including a portion overlying said flange, and yielding means for holding the bowl normally fixed in relation to the frame, 45 said means including a lower set of springs positioned about the frame member and vertically aligned beneath the flange, and an upper set of springs vertically aligned with the lower set of springs and positioned above the portion of the bowl which overlies the flange, generally circular abutment means for the upper ends of the upper springs and for the lower ends of the lower springs, and compression members 50 therefor, the compression mem- 55 bers for the lower set of springs connecting the overlying portion of the bowl with the lower abutment means, the compression members for the upper set of springs connecting the flange of the frame with the upper abutment means, the frame being adapted to serve as a guide for the lower set of springs and the lower abutment means, and an additional housing member, positioned 60 above the bowl, adapted to serve as a guide for the upper set of springs and the upper abutment means.
- Signed at Hollywood, county of Los Angeles and State of California, this 24th day of July, 1931.
